SHEET METAL SHIPPING DRUM

Charles H. Rollason, Wheeling, W. Va., assignor
to Wheeling Steel Corporation, Wheeling,
W. Va., a corporation of Delaware

Application October 3, 1930, Serial No. 486,086

4 Claims. (CL. 220—61)

This invention relates broadly to sheet metal drums, and it has for its primary object to provide a shipping drum which includes a readily removable and replaceable head and simple and effective means for securing said head in place.

In describing the invention in detail, reference is herein had to the accompanying drawing, in which—

Figure 1 is a head end elevation of a fragmentary portion of a drum embodying this invention;

Figure 2 is a detail view in longitudinal section, showing the head end of the drum as it appears prior to closing the end of the drum body into retaining relation to the removable head;

Figure 3 is a similar section with the head secured in place; and

Figure 4 is a similar section showing a modified form of head.

Referring to said drawing, 1 designates generally the body of a cylindrical sheet metal drum which has formed therein at a suitably spaced distance from the terminal edge of the head end thereof an inwardly directed, or internal, annular bead 2. The top surface of said bead constitutes a seating ledge 3 upon the inner edge portion of which may rest the under side of the outer edge portion of a circular wooden head 4. Said head has a diameter materially less than the internal diameter of the head end of the drum body, and suitably attached to the outer face of said head, as by means of short, readily removable brads 5, is the inner edge portion of a resilient split ring 6, preferably made of steel, which normally, or in its fully expanded condition, has a peripheral diameter approximating the internal diameter of the head end of the drum body.

A terminal roll 7 is formed on said body by turning or rolling inwardly the metal of the edge portion of the head end thereof subsequent to the mounting upon said seating ledge of the head 4 with the ring 6 occupying attached relation to the latter. Said roll, which constitutes a rim for the end of the drum, occupies closely-seated relation to the ring 6 adjacent to the outer peripheral edge of the latter for maintaining said ring and, consequently, the attached head 4 in firmly seated position. The roll 7 is made of such small size that the internal diameter of the drum at said roll slightly exceeds the diameter of the wooden head 4, thus to allow said head to be withdrawn past said roll after removal of the ring 6.

The ring 6, which may be formed of flat material—that is, of even thickness throughout—is perforated at suitable relatively spaced distances for the reception of the attaching brads 5. Each of the ends of said ring is preferably beveled, as shown at 8, in Fig. 1, to facilitate movement of said ends relative to each other in expanding and contracting the ring. Holes 9 are preferably provided adjacent to each of said ends for the reception of the point of a hook or other instrument by means of which contracting or drawing force may be applied for withdrawing the ring from its seated head-retaining position.

As hereinbefore indicated, the ring is attached to the head prior to introduction of the latter in its seated position within the end of the drum. Thus it is insured that the head shall be properly seated upon the ledge provided therefor and shall not become shifted from said position. When the head is to be removed, the brads 5 may readily be pried up and withdrawn, whereupon said ring may be contracted and withdrawn from beneath the roll 6, thus freeing the head for removal past said roll.

It is to be noted that the bead 2 necessarily possesses such relatively great depth that the ledge 3 formed thereby shall have materially greater width than the diameter of the subsequently formed roll 7.

In the modification shown in Fig. 4, a downwardly dished sheet metal cover or head 4^a is substituted for the wooden head 4 described. Said head 4^a has an annular seating flange 10 which overlies the ledge 3 or which rests upon an interposed gasket 11.

What is claimed is:—

1. A container comprising a container body member having an inward seat portion spaced from an extremity thereof, a closure member on said seat portion of the body member, and an inwardly retractable retaining member in retaining relationship to said closure member, the body member being deformed against the retaining member to hold the closure member in place, the retaining member being substantially unobstructed inwardly thereof for inwardly retractable movement, the closure member being removable from the deformed body member upon inward retraction of the retaining member.

2. A container comprising a container body member having an inward seat portion spaced from an extremity thereof, a closure member on said seat portion of the body member, a retaining member in retaining relationship to said

closure member, the body member being deformed against the retaining member to hold the closure member in place, and means for fixedly fastening together the closure member and retaining member.

3. A container comprising a container body member having an inward seat portion spaced from an extremity thereof, a closure member on said seat portion of the body member, a retaining member in retaining relationship to said closure member, the body member being deformed against the retaining member to hold the closure member in place, and means for fixedly fastening together the closure member and retaining member, said means being accessible while said closure member and retaining member are in position with respect to said body member to permit separation of the closure member and retaining member.

20

4. A container comprising a container body member having an inward seat portion spaced from an extremity thereof, a closure member on said seat portion of the body member, an inwardly retractible retaining member in retaining relationship to said closure member, the body member being deformed against the retaining member to hold the closure member in place, the retaining member being substantially unobstructed inwardly thereof for inwardly retractible movement, and means for fixedly fastening together the closure member and retaining member, said means being accessible while said closure member and retaining member are in position with respect to said body member to permit inwardly retractible movement of the retaining member.

CHARLES H. ROLLASON.
